8 Claims. (Cl. 260—674)

This application is a continuation-in-part of my copending application Serial Number 787,294, filed January 16, 1959, now abandoned.

This invention relates to a solvent extraction process for the recovery of an aromatic component from a hydrocarbon mixture containing aromatic and non-aromatic hydrocarbons. More particularly this invention relates to a process wherein such hydrocarbon mixture is contacted in an extraction zone with a solvent composition which selectively dissolves the aromatic component of the hydrocarbon charge mixture and which contains water and an organic solvent boiling above the aromatic component, forming thereby a resulting raffinate phase comprising one or more aromatic hydrocarbons and an extract phase containing dissolved aromatic component, the extract phase is thereafter separately distilled, yielding an overhead distillate containing only a portion of the extracted aromatic component and a side cut comprising aromatic hydrocarbon and water are separately recovered from the distillation and the aromatic hydrocarbon recovered from the side cut.

In the solvent extraction of aromatic hydrocarbons from a hydrocarbon mixture utilizing a solvent selectively miscible with the aromatic component of the mixture, the solvents utilized for this purpose generally contain a definite proportion of water to thereby increase the selectivity of the solvent for the aromatic component of the feed stock and to increase the capacity of the solvent to reject the non-aromatic components in the feed stock, herein referred to as raffinate. Thus, by virtue of such inclusion of water in the solvent composition, the solubility of aromatic hydrocarbons in the solvent, although somewhat reduced in comparison with a non-aqueous solvent, greatly decreases the solubility of raffinate components in the solvent and also reduces the solubility of solvent in the raffinate effluent. The latter factor, however, cannot be completely eliminated and consequently, the raffinate stream inherently contains more or less solvent, depending upon the proportion of water in the solvent composition. Although the quantity of solvent in the raffinate at any instant is relatively small, the cumulative effect of such small amounts of solvent in a stream removed from the process flow and thus otherwise lost, greatly reduces the efficiency and economy of the solvent extraction process. Accordingly, it is desirable that the solvent dissolved in the raffinate stream be recovered therefrom. Such recovery is usually accomplished by counter-currently washing the raffinate with water in a separate washing zone from which an aqueous wash effluent is recovered containing dissolved therein the solvent recovered from the raffinate.

Although the aqueous solvent composition selectively extracts the aromatic components from the hydrocarbon feed stock, it nevertheless dissolves a small but significant quantity of raffinate components having essentially the same boiling point as the aromatic extract hydrocarbon. If these are not removed from the extract or rich solvent phase prior to the recovery of the aromatic component therefrom in the subsequent extract distillation or "solvent stripping" stage, the normally small amount of raffinate components dissolved in the rich solvent tend to distill over with the aromatic extract product, and since these hydrocarbons have essentially the same boiling

2

point as the desired aromatic extract, they generally cannot be readily removed from the aromatic product by subsequent distillation. When the aromatic product is desired in a high state of purity, as, for example, in the production of benzene of nitration grade quality, containing 99+ percent benzene, a slight contamination of the aromatic product with raffinate produces a product which does not meet nitration grade specifications and is not readily subject to supplementary methods of purification. For this reason, the rich solvent stream (as it is formed in the extraction zone and containing raffinate-type solute) is desirably contacted (preferably under countercurrent flow conditions), prior to the recovery of aromatic extract therefrom in the so-called stripping stage, with a light paraffin-aromatic mixture recovered as overhead distillate from the rich solvent stripping column. During such countercurrent contact of the rich solvent with the light paraffin-aromatic mixture, known in the art as reflux, the raffinate dissolved by the solvent (i.e., of the same boiling point as aromatic extract) is displaced from the rich solvent prior to the removal of the latter from the solvent extraction zone, the raffinate thus being replaced by the light paraffin and aromatic components of the reflux. The rich solvent leaving the solvent extraction zone, thereby, contains dissolved aromatic extract and light paraffin present therein by virtue of the contact between the light paraffin-aromatic reflux and rich solvent stream in the lower portion of the solvent extraction zone.

In the subsequent stripping stage of the process the hydrocarbon solute is distilled from the rich solvent with the aid of steam formed by distillation of the aqueous solvent composition and/or by the injection of water into the lower or so-called reboiling section of the stripping zone which is maintained at a temperature above the boiling point of the solvent; the overhead product from the stripping zone will then contain substantially all of the light paraffins of the reflux as well as a portion of the aromatic component of the rich solvent stream. When the aromatic component of the hydrocarbon feed stock consists of two or more species of different boiling points, the reflux will contain a portion of the most volatile aromatic component of the rich solvent stream. The remaining portion of the aromatic component of the rich solvent is then distilled from the stripping zone as a side cut containing in addition to the volatilized aromatic hydrocarbon(s), vaporized water and organic solvent; at the same time the rich solvent residue obtained from the reboiling section of the stripping zone will contain organic solvent substantially free of hydrocarbon solutes and will generally contain water in an amount depending on the conditions of temperature, pressure and the quantity of water or steam injection employed in the reboiling section. By appropriate selection of these conditions it is possible in the known solvent extraction process and desirable also in the process of the present invention to reconstitute the solvent composition in the stripping zone so that the effluent from the bottom portion of the reboiling section thereof contains the same proportion of water and organic solvent as the desired solvent composition contracted with the hydrocarbon feed stock in the extraction zone.

A principal object of this invention is to provide a simplified and highly economical process for the recovery of a raffinate-free aqueous phase from the raffinate washing stage of the process to thereby enable the re-use of the recovered aqueous phase in the rich solvent stripping stage as a source of stripping steam and to thereby also recover the solvent contained in the aqueous phases of both the stripper side-cut fraction and the raffinate wash effluent. A further object of this invention is to reduce to a minimum the need for water from extraneous sources in the recovery of a substantially pure-solvent-

free aromatic extract and a solvent-free non-aromatic raffinate, each separately recovered from a mixture of aromatic and non-aromatic hydrocarbons with the aid of a water-containing solvent composition.

The separation process of this invention is characterized principally by the feature of utilizing the aromatics dissolved in the aqueous phase of the stripper side-cut fraction to displace raffinate-hydrocarbons dissolved in the aqueous phase recovered from the raffinate wash stage of the process to thereby produce recovered aqueous effluents free of contaminating feed stock boiling range raffinate hydrocarbons prior to the distillation of the recovered aqueous phases for the purpose of recovering solvent therefrom.

A more specific embodiment of this invention concerns an aromatic hydrocarbon recovery process which comprises contacting a hydrocarbon mixture containing aromatic and non-aromatic hydrocarbons with a solvent composition which selectively dissolves the aromatic component of said mixture and which contains water and an organic solvent boiling above said aromatic component, separating a resulting raffinate phase comprising said non-aromatic hydrocarbon from a rich solvent phase containing dissolved aromatic component, subjecting said rich solvent phase to distillation to thereby form an overhead distillate containing only a portion of the extracted aromatic component and a side-cut fraction containing water and said aromatic hydrocarbon, separating an aqueous side-cut condensate containing solvent and dissolved aromatic hydrocarbon from a substantially aromatic hydrocarbon extract, washing said raffinate with water and separately recovering an aqueous wash effluent containing solvent washed from said raffinate, thereafter mixing said aqueous wash effluent with at least one of the group consisting of: (1) said overhead distillate, and (2) said aqueous side-cut condensate, recovering substantially raffinate-free aqueous solvent from the mixing step and supplying said aqueous solvent to said distillation stage.

Most advantageously, the aqueous phase resulting from the washing of the raffinate is separated from the washed raffinate and then mixed with the aqueous phase recovered from the side-cut stripper and overhead condensates of the rich solvent stripping stage, the resultant mixture is separated into a hydrocarbon phase and an aqueous phase substantially free from raffinate components, and the resultant mixture of aqueous phases is supplied to the reboiling section of the rich solvent stripping stage as a source of stripping steam therein.

Before the overhead distillate of the rich solvent stripping stage is separated into an aqueous phase and hydrocarbon phase suitable for recirculation to the extraction zone for reflux purposes, one of the preferred embodiments of the present invention provides for utilizing the aromatic component present in this light distillate to displace the raffinate paraffin dissolved in the aqueous wash effluent of the raffinate water-washing step, and this aqueous wash effluent is thereafter charged into the rich solvent stripping zone as a source of stripping steam therein. Such additional processing technique will be hereinafter further described.

Typical hydrocarbon mixtures containing aromatic components and utilizable as the hydrocarbon feed stock to the present process include hydrocarbon distillate fractions (usually boiling within or near the gasoline boiling range) of natural gasoline or straight-run petroleum distillates, and especially, hydroreformed naphthas which are rich in aromatic hydrocarbons and are particularly valuable as a source of such mononuclear aromatic hydrocarbons as benzene, toluene and xylene.

Solvent compositions which have a preferential solubility for aromatic hydrocarbons generally contain one or more organic compounds containing in the molecule at least one polar group such as a hydroxyl, amino, cyano, carboxyl or nitro radical. In order to be effective in a system of extraction such as the process provided by

the present invention, the solvent component having the polar radical must have a boiling point substantially greater than the boiling point of water which is included in the solvent composition for enhancing its selectivity, and in general, must also have a boiling point substantially greater than the end boiling point of the aromatic component to be extracted from the hydrocarbon charge. Preferably the organic polar compound used in the solvent composition boils above the end boiling point of the hydrocarbon mixture supplied as charge to the extraction zone. In most instances the solvent composition has a greater density than the hydrocarbon charge and is accordingly introduced into the uppermost portion of the solvent extraction zone, thereafter flowing downwardly, countercurrent to the rising hydrocarbon feed stock introduced into the extraction zone at its midpoint or in the lower portion thereof.

Organic compounds for use as the solvent component of the solvent composition preferably are selected from the group of those oxygen-containing compounds which include the aliphatic and cyclic alcohols, cyclic monomeric sulfones, the glycols and glycol ethers, as well as the glycol esters and glycol ether esters. The mono- and polyalkylene glycols in which the alkylene group contains from 2 to 3 carbon atoms, such as ethylene glycol, diethylene glycol, triethylene glycol and tetraethylene glycol, propylene glycol, dipropylene glycol, and tripropylene glycol, as well as the methyl, ethyl, propyl and butyl ethers of the glycol hydroxyl groups and the acetic acid esters thereof constitute a particularly preferred class of organic solvents useful in admixture with water as the solvent composition for use in the present process. A particularly preferred cyclic monomeric sulfone is tetrahydrothiophene-1,1-dioxide. Various phenols, such as phenol and resorcinol and their alkyl ethers, such as, for example, para-cresol and thymol, are also effective solvents for aromatic hydrocarbons. Aliphatic nitriles and cyano-substituted ethers and amines of appropriate boiling point, such as acetonitrile, the di-alpha, di-beta, and di-gamma, propion-nitriles and the diethers and polyalkylene polyamines constitute another group of useful solvents when combined with water in certain proportions to provide solvent compositions having the desired selectivity. The proffered polyalkylene glycols and especially, diethylene, triethylene and di-propylene glycols, containing from 2 percent to about 25 percent by weight of water, constitute especially desirable solvent compositions for use in the present process.

The improvement in solvent extraction to which the present invention is directed involves separating the aqueous wash effluent from the raffinate water-washing step, recovering the aqueous solvent-containing phases from each of the overhead and side-cut distillate fractions removed from the rich solvent stripping column, mixing said aqueous wash effluent with the aqueous solvent-containing phase recovered from the stripping column and/or with the overhead distillate of the stripper column. In this manner, the aromatics present in the overhead vapors or dissolved in the aqueous solvent phase of the stripper distillates are utilized for the displacement of the dissolved raffinate from the aqueous wash effluent of the raffinate water-washing step. The aromatic extract hydrocarbons being preferentially soluble in the aqueous phase, these aromatics effectively displace the raffinate hydrocarbons dissolved in the aqueous wash effluent of the raffinate water-washing step. Accordingly when the wash effluent is subsequently injected into the stripping column as a source of steam therein and for the purpose of recovering the solvent in the wash effluent, the raffinate initially present in the wash effluent is no longer present therein and contamination of the extract product distilled from the stripping column with azeotrope-forming raffinate hydrocarbons is avoided.

The present invention and the improvements effected thereby are explained in greater detail in connection with

the accompanying diagram which illustrates a typical process flow in conformity with this invention. It is not intended however to limit the scope of the invention to the specific solvent, specific process conditions, and particular apparatus arrangement described with reference to this drawing.

Referring to the accompanying diagram, an aromatic hydrocarbon-containing charge, such as the product of a gasoline reforming process containing benzene, toluene and xylenes as aromatic components, is introduced into the process flow through line 1 at a superatmospheric pressure which is sufficient to maintain the charge in substantially liquid phase at the particular temperature maintained within the extraction zone and which may be in the range of from about 10 to about 300 pounds per square inch, or higher. Depending upon the water content of the solvent composition, the temperature of the extraction may be varied to increase or decrease the selectivity and solubility relationships between the solvent and the hydrocarbon feed stock. Utilizing a polyalkylene glycol solvent, for example, containing from 2 to about 25 percent by weight of water, the process may be operated at temperatures of from about 100° to about 300° C. In order to increase the solubility of aromatics in the solvent, while maintaining the selectivity at a high level, the extraction stage of the process is preferably operated at a temperature in the range of from about 125° to about 200° C. with maintenance of liquid phase contact in the extraction zone. For polyethylene glycol solvents, such as triethylene glycol, containing from 5 to about 15 percent by weight of water, the preferred extraction conditions for the present process are temperatures of from about 110° to about 150° C., utilizing solvent to hydrocarbon charge ratios of from about 5 to 1 to about 15 to 1 volumes per volume.

Referring again to the accompanying diagram, the hydrocarbon feed stock at the foregoing temperature and pressure conditions is fed from line 1 at a rate controlled by valve 2 and at a pressure provided by pump 3 into line 4 containing heater 5 which raises the temperature of the hydrocarbon feed stock to the foregoing extraction temperature. The feed stock at the desired temperature and pressure is charged into extraction column 6 at an intermediate point below the solvent inlet (which generally is in the upper portion of the column) and above the rich solvent outlet in the lowermost portion of the column. Lean solvent composition from which hydrocarbon solute has been removed in the stripping stage of the process, is charged through line 7 at the desired temperature and pressure into the upper portion of solvent extraction zone 6.

Solvent extraction zone 6 may be of any type suitable for effecting countercurrent contact between two liquid phases at least partially but not wholly miscible in each other and wherein the relatively more dense solvent may be brought into intimate contact with the relatively less dense hydrocarbon phase. Thus, extraction zone 6 may be a packed column or may contain a series of horizontal, perforated plates through which the liquid solvent flows in dispersed form and in countercurrent flow relationship to an ascending hydrocarbon stream. The recycle reflux stream consisting in part, preferably predominantly, of a portion (usually the lightest portion) of the aromatic extract component present in the hydrocarbon charge, is introduced into zone 6 at a point below the feed stock charge line 4 through line 8. This reflux stream usually is made up predominantly of the stream recovered as overhead distillate from the solvent stripping zone.

As the hydrocarbon feed stock and reflux flow upwardly through column 6 in countercurrent relationship to the descending solvent composition, the solvent selectively extracts the more soluble aromatic hydrocarbon components of the feed stock and selectively rejects the paraffinic and other non-aromatic components which make up the raffinate. The non-extracted residue, herein referred to

as "raffinate," comprises predominantly paraffinic hydrocarbons substantially free of the aromatic hydrocarbons to be recovered as extract product of the process; thus raffinate is withdrawn from the top of extraction zone 6 through line 9, containing pump 10 which discharges the raffinate stream through line 11 into raffinate washing zone 12 for recovery of the normally small but significant quantity of solvent dissolved in the effluent raffinate hydrocarbon stream. Since this stream is customarily employed for blending into gasoline motor fuels, the presence of the solvent therein is detrimental to its use and must accordingly be removed therefrom prior to its use as a motor fuel. Moreover, if the solvent dissolved in the raffinate effluent, even through the quantity of this dissolved solvent is generally small, were not recovered therefrom, its continuous removal from the process in the raffinate would represent a substantial loss on a continuously operating basis, since the raffinate stream does not reenter the process flow. Accordingly, raffinate washing zone 12 is incorporated into the process flow in order to recover the solvent removed from the extraction zone in the raffinate.

In order to effect such recovery of solvent from the raffinate on an efficient basis, however, the aqueous stream used to wash the raffinate must be free of solvent and must be confined to the smallest possible quantity sufficient for the purpose, since excess water must be removed from the recovered solvent solution in order that it may be utilized again in the extraction zone. The most effective aqueous wash stream for this purpose which is recycled within the process flow in order to maintain the total water inventory constant and in equilibrium is that recovered from the overhead or side-out fractions of the stripping column in the operation according to the present process which produce aqueous condensates containing a high proportion of water suitable for washing the raffinate stream removed from the solvent extraction zone. The source of such aqueous streams charged into the top of column 12 through line 51 will be hereinafter more specifically described.

Since the aqueous wash stream is of generally greater density than the hydrocarbon raffinate, countercurrent washing is conveniently effected by introducing the aqueous stream into the top of zone 12, usually a countercurrent contacting column, as the raffinate of lesser density is introduced into the bottom thereof. A resulting washed raffinate from which the solvent composition has been substantially completely removed is withdrawn from column 12 through line 13 at a rate controlled by valve 14 and thereafter removed to storage or to other processing stages accompanying the present extraction process. An aqueous wash effluent containing recovered solvent is removed from the bottom of washing zone 12 through 15 by means of pump 16 which discharges the aqueous wash effluent through line 17 containing valve 18 into an overhead receiver vessel utilized in connection with the solvent stripping stage of the present process, hereinafter referred to in greater detail.

Referring again to the solvent extraction stage of the present process flow, as the rich solvent stream containing dissolved aromatic extract flows downwardly through extraction zone 6, it countercurrently contacts the light aromatic-paraffin reflux introduced into the extraction zone through line 8 in the lower portion of the column. The reflux, in its countercurrent contact with the descending rich solvent, displaces raffinate paraffins which have a tendency to dissolve in the rich solvent stream to a small extent; in effect, the rich solvent prior to its removal from the extraction zone is countercurrently washed with light, more soluble aromatics and/or light paraffins which replace the raffinate solute from the rich solvent into the upwardly flowing hydrocarbon phase and thus ultimately into the raffinate effluent from the extraction zone. The resulting rich solvent, which now contains dissolved aromatic extract and reflux components and is free from raf-

finate hydrocarbons boiling in the same range as the aromatic solute is removed from the bottom of extraction zone 6, through line 19 at a rate controlled by valve 20 and transferred by means of pump 21 through line 22 into the upper portion of rich solvent stripping zone 23 for recovery of the hydrocarbon solute therefrom. Stripping zone 23 generally contains a reboiler 24, in the lower portion of the column which supplies additional heat to the rich solvent residue accumulating in the lower portion of column 23 for stripping the last traces of aromatic solute from the rich solvent prior to its removal from the stripping zone.

In the preferred manner of operating the solvent extraction process, extraction zone 6 is maintained at a pressure sufficient to provide essentially liquid phase conditions in the extractor at the particular extraction temperature, as aforesaid. Thereafter, the resulting rich solvent in liquid phase is transferred into stripping zone 23 wherein the pressure on the rich solvent is reduced (preferably in several stages) while maintaining the liquid residue substantially at the same temperature by means of reboiler 24. The vapor overhead and side-cut fractions thereby isothermally flashed from the rich solvent are predominantly hydrocarbon, but since the water and organic solvent components of the rich solvent stream also have significant vapor pressures at the temperature of the rich solvent, water and solvent are also present in the vapors, the quantity of the latter components increasing as the boiling point of the respective fraction increases.

The overhead vapor flashed from the rich solvent contains substantially all of the light paraffin components (e.g., C₅, C₆ and C₇ paraffins) of the hydrocarbon reflux, which is present in the rich solvent by virtue of having replaced paraffins of greater molecular weight in the extraction zone. The overhead also contains a large proportion of the lightest (lowest molecular weight) aromatics (e.g., benzene) present in the feed stock which distills overhead with the light paraffins during the stripping operation and thus make up the hydrocarbon reflux recycled to the bottom of the extraction zone. In any event, the reduction in pressure between the extraction and stripping zones is sufficient to vaporize completely the paraffinic component of the rich solvent stream and if necessary, sufficient heat is introduced into the reboiling portion of the column to supply the heat of vaporization required to completely remove all of the paraffin soluble from the rich solvent into the vapor overhead and to effect such vaporization substantially isothermally. The resulting vapor overhead is removed from the top of the stripping zone through line 25 into overhead condenser 26 which liquefies the vaporized components for withdrawal therefrom through line 27 and valve 28 for discharge into receiver 29. The condensate formed by liquefying the overhead vapor stream is a mixture of hydrocarbons and aqueous solvent saturated with the light aromatic component of the vapor overhead. In accordance with the present process, the primarily hydrocarbon portion of the condensate may be separated from the aqueous phase in an auxiliary receiver (not shown), if desired, and separately recycled to extraction zone 6 as recycle reflux while the lower aqueous phase is separately charged into receiver 29 as the source of aromatic for displacement purposes therein. However, in the preferred alternative arrangement, the entire overhead condensate is allowed to enter receiver 29, to thereby provide a source of excess light aromatics therein and a hydrocarbon phase to receive the raffinate components displaced from the aqueous raffinate wash effluent.

The lower aqueous layer accumulating in receiver vessel 29 would normally be saturated with the most volatile aromatic component of the feed stock (such as benzene, for example, when the feed stock is a gasoline boiling range fraction), together with a small amount of solvent vaporized with the hydrocarbon components into the light vapor overhead. In order to recover not only the dis-

solved solvent and aromatic components dissolved in the aqueous portion of the condensate, but also to provide steam for stripping purposes in rich solvent stripping zone 23, the aqueous layer would normally be withdrawn from the receiver vessel and recycled to the reboiling section of stripping zone 23, for the aforementioned purposes. In the present process, however, the aromatic hydrocarbon dissolved in the aqueous phase accomplishes an important auxiliary function comprising the essential inventive concept upon which the present improvement is based. As heretofore indicated, the aqueous wash effluent recovered from the raffinate washing zone 12 contains feed stock raffinate (paraffins) dissolved and/or entrained within the aqueous washings recovered from the raffinate water washing zone 12. Since the quantity of solvent recovered by the raffinate water wash step necessitates recovery of the solvent therein and such recovery is generally effected by charging the aqueous water wash effluent into the stripping zone as a source of steam in the latter zone for stripping solute from the rich solvent, the feed stock raffinate paraffins contained in the aqueous wash effluent would contaminate the aromatic extract product distilled from the stripping zone if not removed from the aqueous effluent prior to discharge into the reboiling section of rich solvent stripping zone 23. Although the aqueous wash effluent could be separately distilled to recover the solvent therefrom, such procedure involves the necessity of providing an additional distillation column, the consumption of large quantities of heat for effecting such distillation and other uneconomical procedures which would otherwise increase the cost of recovering the aromatic extract product in a highly purified form.

In accordance with the process of the present invention, however, the raffinate paraffins present in the aqueous wash effluent are displaced therefrom by preferentially soluble aromatics derived from the stripper overhead itself (which is normally recycled to the solvent extraction zone) or from the aqueous layer collected in overhead receiver 29, the aqueous layer containing dissolved light aromatic distilled from the rich solvent in stripper 23. Through such mixing of the two aqueous streams, one containing a dissolved light aromatic from the overhead receiver and the other containing dissolved raffinate paraffins from the raffinate washing zone, or by mixing the water wash effluent with stripper overhead hydrocarbons the raffinate paraffins present in the aqueous wash effluent are displaced therefrom into the hydrocarbon phase collecting in the overhead receiver, forming thereby a lower aqueous layer in receiver 29 containing only preferentially soluble aromatic hydrocarbons, the raffinate paraffins initially present in the aqueous wash effluent being displaced into the hydrocarbon layer simultaneously accumulating in receiver vessel 29. By virtue of such displacement, the aqueous phase subsequently withdrawn from receiver 29 and recycled to rich solvent stripping zone 23 contains only the desired aromatic product as the dissolved hydrocarbon phase. When subsequently vaporized in zone 23, these aromatic hydrocarbons are recovered as part of the aromatic product of the process, not contaminated by feed stock raffinate hydrocarbons. Aromatic products exceeding nitration grade specifications (i.e., of 99+ percent purity) are thereby made feasible.

As a result of the hydrocarbon exchange which occurs in receiver 29, the hydrocarbon layer accumulating above the aqueous phase in the receiver is a mixture of light paraffins (if present), the lightest aromatic component of the feed stock (such as benzene), both of which are distilled overhead from the rich solvent in stripping zone 23, and the feed stock raffinate paraffins displaced from the aqueous wash effluent admitted to receiver 29 from the raffinate wash zone. The upper hydrocarbon layer is recycled to the bottom of solvent extraction zone 6 to provide the recycle reflux heretofore described and for the purposes indicated, being withdrawn from receiver

vessel 29 through line 30 at a rate controlled by valve 31 and transferred by means of pump 32 into line 8 which conveys the recycle reflux into the lower portion of solvent extraction zone 6. The volume of light paraffins and light aromatics in the recycle reflux is generally sufficient to effect countercurrent washing of the rich solvent phase descending into the lower portion of extraction zone 6; but if insufficient to effect the removal of feed stock paraffins (raffinate) from the rich solvent before the latter leaves the extraction zone, additional makeup paraffin reflux may be introduced into the process cycle at a rate determined by valve 34, from external source through line 33 connecting with recycle line 30. In general, the volume of light paraffin and/or light aromatic present in the recycle reflux stream is sufficient to provide a volumetric ratio of reflux to rich solvent contacted therewith in the lower portion of extraction zone 6 of from about 0.1:1 to about 20:1 or more, preferably from 0.5:1 to about 5:1 volumes of reflux per volume of rich solvent.

The feed stock raffinate paraffins displaced from the aqueous wash effluent of the raffinate wash tower and present in the recycle reflux stream do not hinder the rich solvent washing action of the light paraffins in the lower portion of the solvent extraction zone, since these hydrocarbons join the rising hydrocarbon stream in the solvent extraction zone and are eventually removed from the top of the extraction zone in admixture with feed stock raffinate.

The aromatic-containing aqueous stream utilized as one of the alternative sources of light aromatic for displacing raffinate from the aqueous raffinate wash effluent may be supplied to vessel 29 from the aqueous phase recovered as a portion of the vapor overhead or vapor side-cut from the solvent stripping zone, hereafter described. Both of these streams provide a source of light aromatic which saturates the water simultaneously distilled from the solvent composition with the light aromatic and light paraffins in the overhead distillate. The diversion of this aqueous phase, saturated with aromatic component, into receiver 29 enhances the completeness of raffinate paraffin displacement, since the displacement is a mass action effect which is increased as the volume of total aromatic present in receiver vessel 29 is increased. This supply of aromatic hydrocarbon-saturated aqueous stream is supplied to receiver 29 through line 27, as aforesaid.

As the rich solvent descends through the solvent stripping zone, after leaving the flash vaporization section in the upper portion thereof, it contacts rising vapors of steam and hydrocarbon distilled from the rich solvent in column 23 and by virtue of steam generated from the recycled aqueous washings charged into the reboiling section of column 23. Reboiler 24 is operated at a rate of heat input sufficient to supply the necessary heat of vaporization to complete the distillation of all of the paraffins from the rich solvent stream in the upper section of stripping zone 23, sufficient aromatic solute being distilled with the paraffins to ensure complete removal of the latter paraffins from the rich solvent before aromatic product is taken off as a side-cut vapor. At some point below the flashing section of column 23, the hydrocarbon vapor phase in equilibrium with the solvent composition is completely aromatic in composition and at such point the hydrocarbon component of the side-cut vapors withdrawn from column 23 are entirely aromatic extract. Water vapor, and vaporized solvent composition which also has a finite vapor pressure above the rich solvent phase comprise the remaining portion of the vapors. The latter side-cut is withdrawn from column 23 through line 35, liquefied in condenser 36 and liquid condensate drained therefrom through line 37 and valve 38 into condensate receiver 39. The liquid condensate separates into a lower, substantially aqueous phase saturated with aromatic hydrocarbon extract vaporized with the water and solvent, and an upper, wet hydrocarbon extract phase. The upper hydrocarbon layer consisting of essentially pure aromatic extract when operating the process in

accordance with this invention, is withdrawn from receiver 39 through line 40 and valve 41 as the ultimately desired aromatic product of the process, being thereafter dried and fractionated to separate therefrom, substantially pure aromatic components.

Although the solubility of aromatic hydrocarbons in water is relatively small, the aqueous layer accumulating in vessel 39 contains a significant proportion of dissolved aromatic product, generally from about 0.1 to about 2% by weight of the aqueous phase. The aromatic content is directly proportioned to the temperature of this stream. The lower aqueous phase, containing dissolved aromatic product, thus constitutes a desirable source of the aromatic-containing aqueous stream supplied to receiver vessel 29 for the purpose of displacing feed stock paraffins from the aqueous washings recovered from the raffinate washing zone, thereby supplementing the aqueous, aromatic-containing stream recovered as overhead from the rich solvent stripping zone. When desired, therefore, particularly for the ultimate recovery of a substantially pure aromatic extract product of the present process and in order to enhance the displacement raffinate paraffins from the aqueous phase in receiver 29, the lower aqueous layer in receiver vessel 39 is withdrawn from the bottom of the latter vessel through line 42 at a rate controlled by valve 43 and transferred by means of pump 43 into line 44 which conveys the aqueous phase into receiver 29. The combined aqueous phases supplied to receiver 29 and from which substantially all of the feed stock paraffins have been displaced is now in condition for recycling to the lower portion of the stripping zone to be introduced therein as a source of stripping steam and for the recovery of solvent contained therein. The lower aqueous solvent layer in receiver 29 is withdrawn therefrom through line 45 and valve 46 and discharged into line 47 from which all or only a portion of the aqueous layer is supplied to steam generator 48 which produces the steam for stripping purposes in zone 23.

The treatment of the raffinate effluent from the solvent extraction zone in raffinate washing zone 12 depends upon a constant supply of water to continuously wash the stream of raffinate charged into zone 12. In order to conserve water for this purpose, and to utilize internal sources of water to their maximum effectiveness whereby the internal water supply is maintained constant, the aqueous layers recovered from the vapor condensate receivers which accumulate the stripper overhead and side cut streams from the rich solvent stripping zone may be and are desirably utilized as the source of the water wash. The amount of aqueous stream removed from line 47 for the purpose of supplying raffinate washing zone 12 with water is controlled by valve 49 and pump 50 which discharges the amount of water required for raffinate washing purposes into water recycle line 51, feeding into the top of raffinate washing zone 12.

The lean solvent composition from which the hydrocarbon solute has been stripped in the upper portion of zone 23 and which accumulates in the lower portion of the stripping zone is withdrawn from column 23 at an elevated temperature as a result of reboiling and stripping the last traces of the hydrocarbon solute therefrom, the stream being removed through line 52 at a rate controlled by valve 53 and transferred by means of pump 54 into line 55 connecting with heat exchange coil 56 in steam generator 48. Steam is required for stripping purposes in the upper portions of column 23 to reduce the solubility of aromatics in the solvent composition and thereby increase their volatility in equilibrium with the solvent composition. The relatively high temperature of the solvent residue provides an available source of sensible heat from which stripping steam may be generated for injection into the lower portion of stripping zone 23 by heat exchange with the recovered aqueous portion of the side-cut and overhead vapor condensates and the aqueous

wash effluent from zone 12. The steam thus generated at an elevated temperature is discharged from steam generator 48 at a point above the liquid level therein through line 57 which conveys the hot steam into the lower portion of stripping zone 23 at a rate controlled by valve 53. The lean solvent composition from which the reboiling heat has been removed by heat exchange in steam generator 48 is recycled to extraction zone 6 at the desired extraction temperature, depending upon the extent of heat exchange in vessel 48, through line 59 connecting with lean solvent feed supply line 7, thereafter flowing into the top of extraction zone 6 for reuse therein as the lean solvent composition. In the event that additional solvent composition, sufficient to replace losses in the system is required, such quantity, sufficient to make up for such losses, is supplied from solvent reserve through line 60 containing valve 61 and transferred by means of pump 62 into lean solvent feed line 7.

The residue of solvent composition, after distillation of sufficient water therefrom in steam generator 48 to supply the stripping steam requirements of the process in zone 23 and comprising the solvent recovered from the various aqueous condensate sources of the present process, is removed from the lower portion of steam generator 48 through line 63 at a controlled rate determined by valve 64 and transferred under pressure by means of pump 65 through line 66 into lean solvent recycle line 59, thereby recovering the solvent present in the raffinate wash effluent and the aqueous layers of the stripper overhead and side-cut fractions for reuse in the extraction stage. The amount of water distilled from the aqueous solvent residue in steam generator 48 is also controlled by the quantity of water required to rehydrate the lean solvent stream withdrawn from the bottom of the stripping zone to the water level required to meet the lean solvent composition for use as extractant in solvent extraction zone 6. Thus, if the water content of the solvent residue in column 23 is sufficient to meet the lean solvent requirements for extraction purposes, no additional water need be added to the solvent recycle stream from line 66 and the water content of the solvent residue in heat exchanger 48 can be reduced to the lean solvent water level.

The process of the present invention is further illustrated with respect to several of its specific embodiments in the following illustrative examples which, however, are not intended to limit the scope of the invention necessarily in accordance therewith.

In the following examples a series of runs is described which illustrate a selective solvent extraction process operated under various conditions, designed to demonstrate the advantages to be realized by operating the process in accordance with the improvement provided by the present invention. In each case a catalytically reformed gasoline boiling range fraction is utilized as feed stock for the recovery of a mixture of benzene, toluene and xylene, utilizing a diethylene glycol-water mixture as lean solvent composition containing about 8% by weight of water in a countercurrent, liquid-liquid solvent extraction process effected in an extraction column comprising a series of horizontal perforated plates. The extraction stage of the process results in the formation of a rich solvent composition which is thereafter stripped in the presence of steam to recover the mixture of C₆, C₇ and C₈ aromatic hydrocarbons. The latter extract mixture is thereafter fractionally distilled to separate individual fractions of benzene, toluene and xylene. In Run A the aqueous effluent recovered from washing the raffinate stream with water is recycled to the rich solvent stripping zone without prior treatment to thereby recover the solvent contained in the aqueous wash effluent. In Run B the aqueous effluent is separately distilled to remove the hydrocarbons which are dissolved and/or entrained in the effluent, prior to recycling the distillation residue to the solvent stripping zone. Run C embodies the im-

provement comprising the present invention wherein the aqueous wash effluent from the raffinate washing step (containing raffinate paraffins) is mixed in the stripper overhead condensate receiver prior to recycling the resulting combined aqueous layers in the receiver to the reboiling section of the solvent stripping zone and the hydrocarbon layer in the overhead receiver to the bottom of the extraction zone as reflux therein. In each of the following runs, that is A, B and C, the catalytic reformate is fractionally distilled to separate a fraction having a boiling range of from about 40° to about 155° C. and the latter cut is redistilled to remove a fraction boiling from about 40° to about 65° C. which is utilized as light paraffin reflux make-up to the extraction zone and a feed stock fraction boiling from about 65° to about 155° C. The latter feed stock contains approximately 7.0% by weight of benzene, 25.6% by weight of toluene and 30.6% by weight of C₈ xylenes, and ethylbenzene, the remainder consisting of aliphatic paraffin hydrocarbons in the C₆-C₉ range. The feed stock is charged at the rate of 1635 bbl./day, at a pressure of 100 pounds per square inch and at a temperature of 290° F. (144° C.) into the mid-section of a countercurrent solvent extraction column of the aforementioned type containing about 60 actual plates, which represent from about 15 to about 20 theoretical plates. As the feed stock is charged at the foregoing conditions into the solvent extraction zone the aqueous diethylene glycol solvent composition, recovered from the reboiling section of the solvent stripping zone, hereinafter described, is charged at a rate of 24,780 bbls./day and at a temperature of 290° F. and at a pressure of 100 pounds per square inch into the top of the extraction column, thereafter percolating downwardly through the perforations in the horizontal plates against a rising stream of the feed stock charged into the mid-portion of the extraction column. Another stream, herein referred to as a recycle reflux enters the extraction column below the feed stock inlet and more preferably, in the bottom of the extraction column, the reflux being a mixture of benzene and light paraffins containing approximately 88% by volume of benzene combined with C₅ and C₆ aliphatic paraffins derived from the upper hydrocarbon layer of the stripper overhead condensate, mixed with the volatile portion of the catalytic reformate boiling from about 40° to about 65° C., referred to hereinabove as light paraffin reflux make-up. The latter mixture is charged into the bottom of the solvent extraction column at a rate of 2102 bbls./day and at the temperature and pressure conditions maintained in the extraction zone.

The non-extracted portion of the hydrocarbon feed stock, herein referred to as raffinate, is removed from the top of the solvent extraction zone at a rate of 766 bbls./day and is diverted into the bottom of a countercurrent flow raffinate washing zone into the top of which 172 gals./hr. of the recovered lower aqueous phase of the stripper overhead condensate is charged as extractant to remove the small quantity of solvent dissolved in the raffinate stream (approximately 1.7 bbls./day). The recovered, washed raffinate removed from the top of the raffinate washing column contains less than 0.2% by weight of benzene, approximately 0.5% by weight of toluene and about 6% by weight of xylene. The recovered aqueous wash effluent is separately treated in accordance with the procedures herein designated in Runs A, B and C to provide a comparative basis of examination for the different Runs.

In the following Run A the rich solvent stream recovered from the bottom of the solvent extraction column is charged at the temperature and pressure maintained in the extraction column into a solvent stripping zone wherein the hydrocarbon solute in the rich solvent is allowed to flash distill in the upper section of the solvent stripping column and reboiled in the lower portion of the stripping zone to recover the aromatic hydrocarbon extract dissolved in the rich solvent. The rich solvent upon

entering the stripping zone is flashed by successive reductions of the ambient pressure from 100 pounds per square inch to substantially atmospheric pressure, the resulting overhead vapors being liquefied in a water-cooled condenser and collected as overhead liquid condensate in a receiver vessel attached to the condenser. The liquid condensate separates into two phases, an upper layer comprising a mixture of benzene and light paraffin hydrocarbons containing approximately 86% by volume of benzene and a lower aqueous layer which is predominantly water containing a small amount (about 2 percent by weight) of diethylene glycol. The upper layer is withdrawn and mixed with the make-up light paraffin reflux fraction recovered from the catalytic reformate, and charged at a rate of 1102 bbls./day into the bottom of the extraction column as recycle reflux. The lower aqueous layer of the overhead condensate, in the amount of 242 bbls./day, is separately recovered and reserved for use as stripping steam in the rich solvent stripping zone.

A side-cut fraction is removed from an intermediate plate of the solvent stripping column at atmospheric pressure, liquefied in a water-cooled condenser and collected in a side-cut receiver. A lower aqueous layer is withdrawn from the receiver in the amount of 387 bbls./day, combined with the aqueous phase recovered from the overhead vapor condenser and the aqueous wash effluent of the raffinate washing zone. The combined aqueous mixture containing approximately 2.3% by weight of diethylene glycol is charged at a rate of 1530 bbls./day into the reboiling section of the solvent stripping zone, the steam thereby generated rising through the stripping column and vaporizing hydrocarbon solute from the rich solvent.

The aromatic extract (upper layer) accumulating in the side-cut receiver, amounting to 869 bbls./day, is reserved as product. Upon fractionation of the extract in a separate distillation column a benzene overhead boiling from 79.9° C. to 81° C., containing 98.2% benzene is condensed and collected. A toluene cut (98.3% by weight toluene) is separated from the residue in a second distillation column. The residue from the latter distillation, comprising xylenes and ethylbenzene contains 94.8% by weight of C₈ aromatic hydrocarbons. Infra-red analysis of the three aromatic cuts indicates that the impurities present in each of the cuts, although relatively small in amount, consist of aliphatic paraffins boiling in the same range as the desired aromatic products.

In the following Run B the aqueous wash effluent from the raffinate washing zone is separately recovered and distilled in a separate column prior to mixing the distillation residue with the lower aqueous layers recovered from the overhead and side-cut condensate receiver vessels attached to the respective overhead and side-cut vapor lines of the stripping zone. Upon distillation of the raffinate wash effluent, and overhead vapor consisting predominantly of steam, but also containing feed stock raffinate hydrocarbons is recovered from the aqueous residue which contains diethylene glycol in solution. In order to free the aqueous raffinate wash effluent completely of paraffinic hydrocarbons, approximately 1/2 of the volume of the recovered aqueous wash effluent must be distilled in the separate distillation column. Redistillation of the aqueous wash effluent requires a separate column containing about 5 theoretical plates and results in the consumption of an additional 8% of the utility requirements (heat and electrical energy) of the process in which the redistillation is omitted. The recovered aromatic products removed from the side-cut receiver of the rich solvent stripping zone, however, are substantially pure, the benzene fraction consisting of 99.99% benzene has a boiling range of from 80.0 to 80.1° C. The toluene fraction recovered in a separated in a separate column is also of substantially greater purity (99.1% toluene).

In the following Run C the aqueous wash effluent (approximately 172 gals./hr.) recovered from the raffinate wash zone is allowed to run in the receiver attached to the overhead condenser, thereby mixing the aqueous raffinate wash effluent with the aqueous and hydrocarbon layers of the overhead condensate, containing benzene. The hydrocarbon upper layer (predominantly benzene) in the overhead condensate receiver displaces the raffinate paraffins present in the raffinate wash effluent and extracts these hydrocarbons from the aqueous phase, leaving an aqueous phase free of non-aromatic hydrocarbon. By virtue of such mixing the feed stock paraffins dissolved in or entrained in the aqueous raffinate wash effluent are displaced therefrom into the hydrocarbon layer accumulating in the overhead receiver vessel, and are recycled to the extraction column as recycle reflux. The lower aqueous phase collected in the overhead condensate receiver, after removing a portion (172 gals./hr.) for use as the raffinate wash water, was mixed with the lower aqueous layer accumulating in the side-cut receiver vessel and the resulting combined aqueous streams charged at a rate of 1523 bbls./day into the reboiling section of the stripping column. The mixture of C₆-C₈ aromatic hydrocarbons recovered as extract product from the stripping zone upon fractional distillation yielded benzene of 99.99% purity, toluene of 99.4% purity and a C₈ aromatic cut of 98.5% purity. The latter purities were realized without the consumption of additional utilities in either the extraction or stripping sections of the process, compared to the process of Runs A and B, above.

I claim as my invention:

1. An aromatic hydrocarbon recovery process which comprises contacting a hydrocarbon mixture containing aromatic and non-aromatic hydrocarbon components with a solvent composition which selectively dissolves the aromatic component of said mixture and which contains water and an organic solvent boiling above said aromatic component, separating a resulting raffinate phase comprising said non-aromatic hydrocarbon from a rich solvent phase comprising solvent containing dissolved aromatic component, distilling said rich solvent phase, recovering overhead from the distilling step and aqueous condensate comprising extracted aromatic component of greatest volatility and a side-cut fraction comprising a major proportion of the extracted aromatic hydrocarbon, separating an aromatic-containing aqueous condensate from said side-cut fraction, washing said raffinate with water and separately recovering an aqueous wash effluent containing raffinate component and solvent washed from the said raffinate, thereafter mixing said aqueous wash effluent with at least one of said aqueous condensates to displace raffinate component in the wash effluent with aromatic hydrocarbon contained in the aqueous condensate, recovering a substantially raffinate-free aqueous solvent phase from a hydrocarbon phase comprising raffinate displaced from said aqueous solvent, and introducing the resulting aqueous solvent into the rich solvent during the distilling step.

2. The process of claim 1 further characterized by recovering an aqueous phase containing dissolved aromatic hydrocarbon from the overhead of said distilling step and utilizing at least a portion of said aqueous phase as the source of water for washing raffinate.

3. The process of claim 1 further characterized in that said hydrocarbon mixture contains benzene.

4. The process of claim 3 further characterized in that said hydrocarbon mixture contains benzene, toluene and a C₈ aromatic hydrocarbon.

5. The process of claim 1 further characterized in that said aqueous wash effluent is mixed with both said aqueous condensates.

6. The process of claim 1 further characterized in that the hydrocarbon mixture formed by mixing said aqueous wash effluent with aqueous condensate is charged into the solvent extraction zone above the point of withdrawing rich solvent from said extraction zone.

7. The process of claim 1 further characterized in that said aqueous wash effluent is mixed with the aqueous condensate removed overhead from the distilling step.

8. The process of claim 1 further characterized in that said aqueous wash effluent is mixed with the aqueous condensate separate from said side-cut fraction.
